UNITED STATES PATENT OFFICE.

LESLIE H. BURLIN, OF CHICAGO, ILLINOIS.

DESIGN FOR BRACE MEMBER FOR FURNITURE OR SIMILAR ARTICLES.

Application filed June 19, 1924. Serial No. 9,911. Term of patent 7 years.

To all whom it may concern:

Be it known that I, LESLIE H. BURLIN, a citizen of the United States of America, residing at Chicago, in the county of Cook and State of Illinois, have invented a new, original, and ornamental Design for Brace Member for Furniture or Similar Articles, of which the following is a specification, reference being had to the accompanying drawing forming a part thereof, and in which Fig. 1, is a perspective view and Fig.

2 is a side elevation of a brace member for furniture or like article showing my new design.

My brace member for furniture or similar articles is made and sold as a complete and separate article of manufacture.

I claim:

The ornamental design for brace member for furniture or similar articles, as shown.

LESLIE H. BURLIN.
